(57) **CLAIM**

The ornamental design for a T-shaped threaded spacer for a tile leveling system, as shown and described.

DESCRIPTION

FIG. 1 is a perspective of a T-shaped threaded spacer for tile leveling system, with a threaded portion of the T-shaped threaded spacer;

FIG. 2 is a front elevational view of the T-shaped threaded spacer for a tile leveling system;

FIG. 3 is a right elevational view of the T-shaped threaded spacer for a tile leveling system;

FIG. 4 is a top plan view of the T-shaped threaded spacer for a tile leveling system;

FIG. 5 is a rear elevational view of the T-shaped threaded spacer for a tile leveling system;

FIG. 6 is a left elevational view of the T-shaped threaded spacer for a tile leveling system; and,

FIG. 7 is a bottom plan view of the T-shaped threaded spacer for a tile leveling system.

The broken away symbols in the drawings indicate that any portion of the article beyond what is shown forms no part of the claimed design.
